FOREIGN PATENT DOCUMENTS

WO 2012066102 A1 5/2012

Primary Examiner — Melanie H Tung*Assistant Examiner* — Lavone D Tabor(74) *Attorney, Agent, or Firm* — David M. Joyal; Joan M. McGillyuddy(57) **CLAIM**

The ornamental design for an ergonomic applicator, as shown and described.

DESCRIPTION

FIG. 1 is a front perspective view of an ergonomic applicator according to the invention;

FIG. 2 is a back perspective view thereof;

FIG. 3 is a side view thereof;

FIG. 4 is a front view thereof;

FIG. 5 is a back view thereof;

FIG. 6 is a side opposite that shown in FIG. 3;

FIG. 7 is a top plan view thereof; and,

FIG. 8 is a bottom plan view thereof.

The portions of the applicator illustrated in broken lines form no part of the claimed design.

1 Claim, 2 Drawing Sheets(56)
